UNITED STATES PATENT OFFICE.

JAMES W. OHLMAN, OF MASSILLON, OHIO, ASSIGNOR TO THE RELIANCE MANUFACTURING COMPANY, OF MASSILLON, OHIO, A CORPORATION OF OHIO.

APPARATUS FOR AND METHOD OF MAKING WASHERS.

1,288,971.

Specification of Letters Patent. Patented Dec. 24, 1918.

Application filed April 22, 1918. Serial No. 229,920.

To all whom it may concern:

Be it known that I, JAMES W. OHLMAN, a citizen of the United States, residing at Massillon, in the county of Stark and State 5 of Ohio, have invented certain new and useful Improvements in Apparatus for and Methods of Making Washers, of which the following is a specification.

This invention relates to an apparatus for 10 and method of making washers. These washers are virtually of divided or split annular or ring form and are used largely in railway construction and similar fields. In railway use they constitute part of a nut-lock. In an application for patent filed by 15 E. W. Hart for wire coiling and cutting machine on December 8, 1916, Serial No. 135,720, is shown a structure for coiling a wire or similar stock and cutting it to form 20 such a washer. A washer made by the machine of said application or in some other fashion, is subsequently and by an entirely different machine, offset at its ends to produce one or more biting teeth. One of the 25 primary motives I have in view is the provision of an apparatus by which the washer can be made complete; that is a washer can be produced which is off-set at one or both terminals. The off-setting to produce the 30 teeth can be secured within the scope of the invention in a variety of different ways and preferably is at the ends of the split or divided annulus. I have selected for illustration a structure involving the invention and 35 suitable for carrying the method into effect. To enable those skilled in the art to comprehend both the apparatus or machine and method, this structure and its mode of action will be set forth fully in the following description. I do not necessarily confine myself to this particular disclosure; I may depart therefrom in a number of ways within the scope of the invention defined by the 40 claims following said description. It is evidently desirable, although it may not always be necessary, that the split annulus or washer at its ends be furnished with biting teeth, and although their disposition may vary, I prefer generally speaking, that they 45 extend in a direction conforming practically tangentially to the ends of the washer and opposite respectively to each other, so that for illustration when the washer is used in the case of a rail joint, one tooth will abut 50 against and bite into the fish-plate, while the

adjacent tooth will similarly act with respect to a nut, both constituting a part of the joint.

Referring to said drawings:

Figure 1 is a side elevation of the machine. 60

Fig. 2 is an elevation of the lower portion of the machine as seen from the opposite side from that appearing in Fig. 1.

Fig. 3 is a horizontal section on the line 3-3 of Fig. 2, looking in the direction of the 65 arrow.

Fig. 4 is a cross section on the line 4-4 of Fig. 3, looking in the direction of the arrow, and

Fig. 5 is a view corresponding practically 70 to Fig. 4 but without the stop positioned.

Like characters refer to like parts throughout the several views.

I have shown parts of the machine with 75 permission of the applicant in the case involving the invention of the application already identified, this because my invention works with advantage in conjunction with said machine. As will be inferred I am in no manner limited in this particular, because 80 the machine or apparatus may be of a radically different form. In view of this circumstance it is of course not necessary for me to go into detail with the admittedly old structure any more than to indicate the action of the new points and also the way of 85 carrying the method into effect.

The framework for supporting the different parts of the machine involves a base as 90 2 and a standard or upright as 3 rising therefrom. The stock as 4 from which the washers are formed, is practically rectangular in cross section and as in said application is intermittently fed. On the base 2 is a table or plate as 5 which may be bolted in 95 position as by one or more bolts 6 and which has at its outer end the pendent flange 7 to which is bolted as at 8 the pendent flange of the auxiliary frame member 9, which is furnished with anti-friction rollers 10 between 100 which the wire stock 4 is guided and fed.

The auxiliary frame 9 sustains the superimposed rollers 11 between which the wire 4 passes and the peripheries of these rollers engage the wire and actually feed the same 105 toward the forming and cutting means. Co-axial with the lower roller 11 is a ratchet wheel 12 operable by the pawls 13 which in turn are associated with the rocker 14 to which is pivoted the pitman 15 having a 110

crank connection as 16 with the main shaft 17. The main shaft is generally continuously operative. On the upper stroke of the pitman 15 through the primary influence 5 of the said main shaft, the rod or link 14 constituting a suitable carrier for the pawls, will be elevated so as to carry the pawls idly back over the teeth of the ratchet wheel 12. On the opposite or down stroke of 10 the pitman the pawls will turn the ratchet wheel 12 and obviously effect the rotation of the lower wheel or drum 11, and the latter in turn will effect a similar function of the upper wheel or drum, so that the stock 4 will 15 be advanced, the amount of advance being virtually equal to the length of an annulus, ring or washer to be produced. The foregoing is clearly but one of many different ways by which the stock or wire can be advanced.

After the wire 4 or other stock from a reel or other suitable source of supply, passes under the action of the straightening and guide rollers 10, it is as I have explained, presented to the superposed feed rollers 11 which move it toward the coiling, cutting and off-setting means hereafter more particularly described.

The body of the plate 5 supports the foot 30 20 of the block 21 which as shown stands practically upright or vertical. The foot or flange is fastened to said plate 5 by screws 23, of which there are a convenient number. This block constitutes a suitable 35 carrier for a mandrel as 24 which instead of being disposed horizontally as in the application already identified, is upright or vertical. This mandrel is practically in the form of a half cylinder and it is united with 40 the body of the block 21 in some desirable way so as to be rigid therewith. What might be considered as the forward, lateral portion of the block or carrier 21 is on a bevel or slant as at 25, the upper surface of 45 the said block or carrier being apertured or recessed as at 26, the back of the aperture, recess or cut away portion having a groove or channel 27 continued only part of the length of the same, the entering end of the 50 channel, however, being virtually of arcuate form in cross section so as to obtain a proper hold upon the stock or wire as the same is advanced, the advance being toward the right for illustration in Fig. 3.

The upper surface of the block or carrier 55 21 has a second cut away portion 28 in which is supported for free rotation the anti-friction roller 29 constituting a factor in the production of a ring or rings, a plurality of the rings as will be clear being formed in the present case. As a matter of fact two of the rings are thus produced by the structure shown. The peripheral portion of the roller 29 extends for a slight 60 distance across the concaved surface 27, in

view of which circumstance the periphery of said roller will be encountered by the stock as the same is advanced. The curved surface of the mandrel 24 it should also be noticed, is spaced from the bottom or back 70 of the concavity 27 a distance agreeing practically with the thickness of the stock. It will be supposed that the stock is fed forwardly and that it enters the cut away portion or recess 26 and enters the groove, channel or concavity 27. Obviously the groove or concavity curves or bends the forward end of the stock, the bent end of the stock as the latter continues its feed encountering the peripheral portion of the free roller 80 29, the feed of the stock continuing until two complete helices are formed about the mandrel 24 at which point the two superimposed coils are in readiness for the dieing and cutting operation or as it might be considered, actions.

There is a lower die member 30 and an upper die member 31. In the present case one of these members is stationary and the other is movable, being given an intermittent 90 reciprocation. As a matter of preference the lower die member 30 is fixed while the upper one is mounted for intermittent reciprocation. Although the two die members as I have considered them, consist each 95 of two separate parts, this may not always be necessary; obviously they are susceptible of easier production when of sectional form. The lower die member as shown is rigid with the carrier 21 and consists of complementary plates 32 and 33 practically rectangular in cross section. These plates are connected together in some suitable way as by bolting. Their upper surfaces 34 and 35 on which the superimposed formed rings lie, 100 are flat or at least so for the major part thereof. The upper surface 34 of the part 32 has on its inner side the channel or rabbet 36 which is on a slant or angle sloping downwardly toward the companion section or 110 block 33. It will be understood that the adjoining or abutting faces of these two sections are flat. From the inner side of the member 33 there rises the bead or projection 37 which in the present case is of a 115 cross sectional form agreeing with the groove or channel 36.

The upper die member comprises the sections 38 and 39, these two sections abutting like the lower two, flatwise against each 120 other and being held as by screws 40 in the holders 41 connected with the head 42 practically in the manner shown in said application. It will be understood that as the head 42 reciprocates, the dies 30 will be given 125 a corresponding reciprocation. This die-carrying head 42 is operable by the pitman 43 connected with an eccentric 44 on the main shaft 17. The main shaft is intermittently thrown into action through the agency of 130

a clutch controlled by the lever 45 also as shown in said application. On the manipulation, therefore, of the lever, the shaft 44 will be operated and on each complete turn 5 will impart to the head 42 a full reciprocation.

The lower faces 46 and 47 of the sections 38 and 39 are flat but are not, like the faces 34 and 35 flush, the face 47 being situated 10 above the face 46. Or as it might otherwise be put, the interval between the faces 35 and 48 is greater than that between the faces 34 and 46, the difference being practically equal to the thickness of two rings 15 which are to be formed. The member 39 has on its inner side the rabbet 48, the cross sectional form of which agrees approximately with that of the bead 37 and also of the rabbet or channel 36. The section 38 20 has at its lower end the bead 49 which agrees in shape with the bead 37. This bead 49 is obviously of acute angular form in cross section and with the bead 37 coöperates to cut the stock. The beveled lower end of the 25 bead 49 actually performs the cutting operation, while the bead 37 acts practically as an anvil during the cutting operation, although as I will later explain there is in addition to the cutting action, a forming 30 action, this forming action being to offset the terminal portions of a cut ring or washer. Not only is a ring cut and its end or ends deflected, but an end or ends thus deflected acting against a similar blank or 35 portion of the wire deflects the same which is a consideration of importance. As a matter of fact it is within the bounds of possibility that a previously cut blank formed to produce a washer, may when an 40 end or ends are deflected apply pressure to an adjoining blank generally below the same, to correspondingly off-set the latter. Obviously it is of the utmost advantage when the cutting and deflecting actions are 45 virtually contemporaneously accomplished.

The stock or wire 4 is advanced for instance toward the left in Fig. 1 and right in Figs. 2 and 3 in the manner already described. As the leading end of the stock 50 enters the groove 27, the stock is curled up as shown for instance in Fig. 3, the motion continuing until there are at least two full coils or annuluses upon the lower die 30. On the descent of the upper die 31, it will 55 strike the upper coil of the two, and the cutting edge 50 on the lower end of the acute angular bead 49 of the stock into the rabbet 48 and the bead 49 forcing the opposite end of the cut stock into the rabbet 60 36, the consequence being that as the helix is cut through to form a ring, the ends of the ring being cut, will be projected upwardly and downwardly into the channels 48 and 36 by the beads 37 and 49 respectively. The ring thus formed on the rising

of the die 31 will fall away at which point the stock will be further advanced to repeat the action. As will be evident this cut away washer will have its end portions oppositely deflected as illustrated for example 70 by Fig. 4.

What I claim is:

1. A method which comprises forming stock into a plurality of adjoining helices, cutting through one of the helices to produce a split washer, deflecting a portion of a helix during the cutting operation and in causing the deflected portion to similarly deflect the corresponding portion of an adjoining helix. 80

2. A method which comprises forming stock into a plurality of adjoining helices, cutting through one of the helices to produce a split washer, deflecting a portion of a helix during the cutting operation at the 85 cut end and in causing the deflected portion to similarly deflect the corresponding portion of an adjoining helix.

3. A method which comprises forming stock into a plurality of adjoining helices, 90 cutting through one of the helices to produce a split washer, deflecting a portion of the helix at the same time the cut is being made, and at the same time causing the corresponding portion of an adjoining helix 95 to be similarly deflected.

4. A method which comprises adjoining a plurality of helices, cutting through one of the helices to produce a split washer, deflecting oppositely the end portions of the 100 helix during the cutting operation at the cut, and in causing a deflected portion to correspondingly deflect a similar portion of an adjoining helix.

5. A method which comprises adjoining 105 a plurality of helices, cutting through one of the helices to produce a split washer, oppositely deflecting the end portions of the helix at the cut during the cutting operation and at the same time causing a part 110 of an adjoining helix to be also deflected.

6. A method which comprises forming stock into a helix, cutting through the helix to produce a split washer, and deflecting a portion of the helix at the cut during the 115 latter operation to secure a biting tooth in the washer.

7. A machine for making washers comprising means for forming stock into a plurality of adjoining helices, and means for 120 cutting through a helix to form a split washer, at the same time deflecting a part of the stock during the cutting operation to produce a tooth and for causing the deflected part to press against the corresponding part of an adjoining helix to similarly deflect the same. 125

8. A machine of the class described comprising a die member, a mandrel in correlation with the die member, means for feed- 130

ing wire stock around the mandrel to form superposed coils upon said die member, a second die member, and means for effecting a relative movement of the die members, 5 said die members having means which co-operate to cut through the upper helix to form a split washer, at the same time deflecting the ends of the split washer during the cutting operation to produce teeth and 10 for causing the deflected part of said split washer to press against the corresponding part of the adjoining helix to similarly deflect the same.

In testimony whereof I affix my signature in the presence of two witnesses.

JAMES W. OHLMAN.
